Specification of Letters Patent. Patented Apr. 11, 1911.

Application filed May 5, 1910. Serial No. 558,472.

To all whom it may concern:

Be it known that I, HEINRICH DREWELL, subject of the German Emperor, residing at Charlottenburg, Germany, have invented 5 new and useful Improvements in Type-Setting Apparatus, of which the following is a specification.

My invention relates to apparatus for eliminating incorrect groups of holes in 10 perforated bands for automatically setting type.

In my United States Letters Patent No. 970,694, dated September 20th, 1910, I have described a device by means of which, when 15 setting type by means of register bands any errors can be made inoperative when making the band, definite groups of holes in the band, which represent lines, words or individual characters, being made inoperative. In this arrangement the type space indicating device must be correctly set in each 20 case, which operation is effected by the paper carriage of the typewriter connected with the band perforating device being moved backward. As the feed of the paper carriage 25 corresponds exactly with the width of the printed letter to be set, every optional group of characters can be made inoperative, the position of the paper carriage or the written line indicating the correct length to be adjusted. The composer, however, who is making 30 the band must pay considerable attention to the adjustment of the paper carriage in the event of its not returning into the position for beginning a line. A rough adjustment of the carriage may lead to incorrect 35 length of line. According to my present invention the paper carriage is adjusted correctly automatically both when doing away with a defective line, and also when 40 removing incorrectly written words which occurs most frequently. In this manner, inexact 45 adjustments are avoided.

According to the above mentioned co-pending application the perforated word 50 separating symbol, which causes the space member to be set, forms the one limit of a group of holes which represents an incorrectly written word which is to be made inoperative. Now according to my present invention, when perforating this symbol a stop or abutment is adjusted which limits the 55 backward movement of the paper carriage in the event of the word last written being removed. The stop is adjusted at each pressure on the word separating key before the

paper carriage is fed forward by depressing the word separating key. For this purpose the stop is caused to follow the movement of the paper carriage or of an intermediate member connected therewith the amount of 60 the total width of the word last written until it contacts with a second stop arranged on the paper carriage or on an intermediate member. The first stop is fixed again until the next time the word separating key is 65 used. At the end of the line the stop together with the paper carriage is returned into the position for beginning a line.

The keys by means of which incorrectly 70 made groups of holes are made inoperative are designated hereinafter as word-canceling key and line-canceling key. In addition the line-separating key and the word separating key come into consideration. All the other keys are designated briefly as type 75 keys, whether they are used for setting characters or blanks.

One illustrative embodiment of my invention is represented in the accompanying 80 drawings, it being assumed that a paper carriage of the typewriter connected with the perforating apparatus is used as type space indicator as described in my United States Letters Patent 851504 and in the before mentioned co-pending application. My 85 invention is not limited, however, to this form. On the contrary, type space indicators of every kind can be provided with the means according to this invention and be thereby arranged for correcting parts of 90 matter. Also, the mechanical devices can be varied in manifold ways without departing from the spirit and scope of my invention.

In said drawings:—Figure 1 is a side elevation of the combined type-writer and perforating machine; Fig. 2 is a plan view of those parts of the apparatus comprised in the hereinafter described invention; Fig. 3 is a rear elevation of the apparatus, the rear wall having been removed in order to show 95 the rear part of the apparatus; Fig. 4 is a plan view showing the perforating device; Fig. 5 shows the same device in transverse section, and Fig. 6 shows the driving or striking frame of the perforating device; 100 Fig. 7 is a section through the device for moving the paper carriage; Fig. 8 shows the interior arrangement of the clutch between the ratchet mechanism and the paper carriage; Fig. 9 part of the clutch in elevation, 110

and Fig. 10 a side elevation of the perforating apparatus on an enlarged scale.

Referring to the drawings, in the body or frame 1 of the typewriter the type levers 90 and 91 are mounted in suitable manner and connected by draw rods 92 with levers 93. These are arranged on shafts 94, which, on the one hand, carry at one end levers 95 and are so connected by these with the keys 96 that, when a key is depressed, one of the shafts 94 is rotated, and the levers 93 act by means of the draw rods 92 on the type levers 90 so that the type 97 corresponding to the key which has been depressed strikes 15 against the platen roll, whereby an impression of the type is obtained by means of the ribbon 98 located between the type and the platen roll. On the other hand, the shafts 94 are carried at their other end in the frame 20 of the perforating apparatus and are journaled therein at 100 and 101. They traverse a number of plates 102^a, 102^b and 102^c, 102^d, as well as eleven plates 103. The plates 102^a to 102^d influence the feeding mechanism of 25 the paper carriage, while the plates 103 effect the selection of the punches. When any key is depressed the corresponding shaft 94 is rotated and plates 103 or 102^a to 102^d are displaced. This displacement is brought 30 about as follows:—In each of the plates 102^a to 102^d and 103 is provided for each shaft a recess 104 and within this recess two teeth or shoulders 105 and 106 Fig. 5. On the periphery of each shaft 94 are ribs or projections 35 107 and 108 arranged diametrically opposite one another. But the projections 107 and 108 are so displaced longitudinally of the shaft relatively to one another that a gap on the one side always corresponds to 40 a rib on the other side. The shafts 94 are divided into two groups as seen in section in Fig. 5. Those located to the left in Fig. 5 are rotated clockwise when a key is depressed, whereas those on the right are rotated counter-clockwise when a key is depressed. But the plates 102^a to 102^d and 45 103 are always displaced in the same direction, namely in that shown by the arrow 109 in Fig. 5. The shoulders 105 and 106 in the recesses of the plates and the projections 107 and 108 on the shafts 94 are positioned 50 correspondingly. When a shaft on the left of Fig. 5 rotates the bottom projection 108 of this shaft coacts with the shoulder 106 opposite to it and moves the plate, in which the shoulder 108 is located, from the right to the left. During this rotation the projections 107 in those plates which are not to be 55 displaced are placed in front of the shoulders 105 and prevent the plates in question being moved. It is obvious from this that the two projections 107 and 108 need never be in one and the same recess, but that, on the contrary, only one of the projections 108 60 may be at any time in the recess of each

plate. On the right-hand side the corresponding projection and shoulder are located reversely, *i. e.* the projection 108 is above and the projection 107 and shoulder 105 are below the shaft 94.

Each of the plates 103 has an extension 110 running out into a hook 111. The latter engages in a hook 112 of an angle lever 113 which is mounted to rock at the end of the punch 114 and has three arms, of which the arm 113 has, besides the hook 112, an extension 115. When the hook 111 releases the hook 112, which occurs in consequence of the plate 103 in question being moved owing to a key being struck, the angle lever 113 rocks under the action of the spring 116 about the round head 117 of the punch 114, and the extension or shoulder 115 arrives in front of the striking bar 118. Whenever a key is struck two of the plates 103 are moved, 80 and each of these plates corresponds to a special punch which is rendered operative in the described manner by the displacement of the plates owing to the extension 115 corresponding to the punch in question arriving 90 in front of the striking bar 118, and when the key moves further a special coupling is released whereby the main shaft 78 of the perforating apparatus is operated. At this shaft is a cam 121 which, when the main 95 shaft rotates, impels the bar 118 forward by means of the roller 122. This forward movement takes place during the third quarter of a revolution of the main shaft and has terminated at the commencement of the 100 fourth quarter. At this moment the withdrawal of the bar 118 begins by means of the angle lever 123 and the roller 124, on which the cam 121 acts, when the forward movement of the striking bar is terminated.

The striking bar 118 is mounted in a frame 125 (Fig. 6), in which are arranged, in addition, two cross-bars 126 and 127 and an additional striking bar 128. When the frame 125 returns, the bar 128 engages behind a shoulder 129 of the punch 114 and returns the punches into their normal position in so far as they had been pushed forward by the bar 118. In order that the hooks 112 may be placed under the hooks 111 a bar 120 is provided secured to a hook 120^a. The frame rocks around the axle 121^a and possesses a lever arm 121^b, at whose end is arranged a roller 121^c. This runs on a cam 121^d secured on the main shaft 78. The cam has two projections 121^e and 121^f. During the return motion of the punches the roller 122^c runs on the dwell of the cam 121^d. The bar 120 is located in the path of the arms 113^a of the angle levers 113. The point of each of these arms is stopped by the bar 120, the angle lever 113 moving so far that the hook 112 engages under the hook 111. When the punch has returned so far that this engagement has taken place,

the extension 121^c lifts the roller 121^c and thereby moves the bar 120 downwardly so that it releases the lever arms 113^a. Consequently the spring 116 pulls the angle 5 lever 113 around so far that the hook 112 lies against the hook 111, whereby further rotation of the angle lever 113 is temporarily prevented. In order that the point 10 of the lever 113^a can slide unimpededly over the bar 120 when the punches are driven forward, at the moment when the punches are driven forward the bar 120 is moved downwardly by the projection 121 of the cam 121^b so that it does not contact with 15 the point of the levers 113^a.

The plates 102^a to 102^d have extensions 130 and 131 which coact with the vertical arms 132 and 133 of angle levers. The horizontal arms 134, 135 of these angle 20 levers form catches or pawls, by which the angle levers 136 are held in their normal position. The angle levers 136 are pivoted to rods 138 in like manner as the angle levers 113 and possess a horizontal arm 137 25 which can be placed in the path of the striking bar 128. This is brought about by the spring 137^a as soon as the arms 136 are unlocked by the angle levers 135, 134. Four rods 138 (Fig. 4) are provided corresponding 30 on the four plates 102^a to 102^d. Each of these plates coacts with an angle lever 132, 134 or 133, 135 and correspondingly, each plate 102^a 102^b 102^c 102^d occasions if displaced the movement of one of these 35 angle levers and the interpolation of an intermediate lever 137 in front of the striking bar 128. Now if the latter together with the frame 125 is pushed forward when the main shaft 120 rotates once, those rods 138, 40 whose levers 137 have been thrown into gear owing to the plates 102^a to 102^d in question having been pushed forward, are driven in the direction of motion of the frame. Pawls 139 are provided on the rods 138 and 45 engage in the ratchet wheels 16, 17, 18, 19 of the feeding mechanism. When one rod 138 is moved forward the corresponding pawl 139 rotates the appertaining wheel 16, 17, 18, 19. These wheels are prevented from 50 moving backward by suitable pawls 140 under the influence of springs 141 (Fig. 7). The number of teeth of the ratchet wheels 16, 17, 18, 19 is various and, correspondingly, the feed of the paper carriage which 55 they occasion is various. The motions of the individual wheels 16 to 18 is added by means of differential gear and imparted to the paper carriage. The mode of operation of the differential gear has been described 60 in detail in my United States Letters Patent #953988, dated April 5th, 1910.

Referring now to Fig. 1, the frame 2 of the paper carriage runs with rollers 3 on rails 4 secured on the body 1 of the type- 65 writer. The platen roll 5 is mounted in

known manner in the paper carriage 2. The devices for securing the paper on the platen roll, for raising the platen roll and for rotating the same are not shown because they may be constructed in optional manner and 70 are sufficiently well-known. Their mode of operation is not relevant to the present invention. On the frame 2 of the paper carriage is secured a rack 10 with which a pinion 11 meshes. The latter is on an axle 12 75 which, on the one hand, is journaled at 12^a in the typewriter and, on the other hand, at 12^b and 12^c in the frame of the perforating apparatus and carries the gear wheel 13. (Fig. 2.) In contradistinction to the ordinary arrangement a spring tends to bring the paper carriage constantly into the position which the carriage occupies when beginning a line. When writing, the paper carriage is fed by feeding mechanism which 80 works against the spring and is driven by the mechanical force serving for perforating the paper band. This arrangement makes it possible for the paper carriage to move backward automatically, after definite keys 85 have been struck, namely after the depression of the end-of-line key, the line-cancelling key or the word-canceling key. The gear wheel 13 meshes with a gear wheel 14 which runs loosely on the axle 15. This 90 axle carries secured on it another gear wheel 22 which meshes with the wheel 21 secured on the axle 20 of the feeding mechanism. This feeding mechanism comprises four 95 wheels 16, 17, 18 and 19 which can be rotated independently one of another (Fig. 3). These wheels are moved by pawls which are coupled in suitable manner, by means of universal bars moved by the keys, with the 100 source of power operating the punching device. The motion imparted to the wheels is added in known manner by differential gearing and imparted to the axle 20, by which the axle 15 is driven with the intermediary 105 of the gear wheels 21 and 22. This axle 110 imparts its rotatory motion to the wheel 14 by means of a detachable clutch comprising two crown wheels 37 and 38. The crown wheel 37 comprises a powerful disk 25 (Figs. 8 and 9) provided at its edge with axial 115 grooves 26. In these grooves rods 27 move axially, said rods being shaped like a ratchet tooth at one end and at the other carry a round extension 28 around which a spring 29 is arranged. Each rod 27 has a flange-like 120 enlargement 30 which limits its displacement. The disk 25 is firmly connected with the axle 15. Between the disk 25 and the flanges 30 is a disk 31 against which the flanges abut and which serves for holding 125 back all the rods 27 against the action of the springs 29. To this end, the disk 31 is integral with a bushing 32 having a flange 33. By means of a lever 34, whose forked end clasps the bushing 32, the latter can be 130

1 moved axially. A casing 35 is pushed over the rods 27, and the disk 25 prevents the rods 27 falling out of the grooves 26 and supports the springs 29 by means of its end 36.

5 The extensions 28 are guided in holes in the end 36. The disk 25 with the projecting ends of the rods 27 formed as teeth forms a crown wheel with movable teeth which can be pressed back individually and independently one of another. This crown wheel will be hereinafter briefly designated "crown wheel 37." Opposite the teeth of the rods 27 is a crown wheel 38 provided with oppositely-directed, fixed teeth and secured to or integral with the gear wheel 14. The latter is free to rotate on the axle 15, and has a stop or abutment 39 which, when beginning a line, lies against a second stop or abutment 40. This second stop is on the 10 arm 41 connected with a crown wheel 42. The latter is also free to rotate on the axle 15. Between the crown wheel 42 and the gear wheel 14 is a spiral spring 43 tending to rotate both the wheels in such manner that the stop 40 lies on the stop 39. Opposite the crown wheel 42 is a crown wheel 45 provided with movable teeth 44. These teeth are moved toward the crown wheel 42 by springs and tend to engage in the ratchet 15 teeth of the latter wheel. On the wheel 45 is also an axially displaceable bushing 46 having flanges 47 and 48. By means of these flanges and with the intermediary of the levers 49 and 50, which engage like forks around the bushing 46, the teeth 44 of the wheel 45 can be displaced and removed from the crown wheel 42. The crown wheel 45 is free to rotate, but is axially non-displaceable on the axle 15 and is prevented from rotating by a nose or projection 51 located between a fixed stop 52 and an elastic stop 53. (Figs. 2 and 7.) The stop 53 is a lever revolvable around a pivot 54 and under the action of a powerful spring 55. By means 20 of the lever 53 this spring presses the nose 51 against the stop 52 and thereby elastically secures the crown wheel 45 in its position. This arrangement forms a buffer device, by which the limit stop for the backward motion of the paper carriage is made elastic so that great wear and tear of the gear wheels and other parts is avoided. The crown wheels 37, 38, 42 and 45 form two detachable clutches, of which one comprises the crown wheels 37 and 38 and the other the crown wheels 42 and 45. The former clutch is disconnected whenever the paper carriage returns, and the latter when the paper carriage returns into the position at the beginning of the line, and, in addition, when perforating the word separating symbol.

25 As the paper carriage is fed various distances which are graduated according to small units, provision must be made in the clutches that the paper carriage is held fast,

independently of the position of the axle 15, exactly at that point up to which it is to move backward and coupled with the ratchet mechanism. To this end, either the crown wheels of the clutches must have very fine teeth or, as in the present instance, special arrangements must be made which assure the paper carriage being finally adjusted. In the illustrative embodiment this is effected by means of the movable teeth of the crown wheels 37 and 45 as follows: The crown wheels 38 and 42 each have 56 teeth. Opposite each of these teeth are the movable ratchet teeth of the crown wheels 37 and 45. The number of teeth of two opposite crown wheels thus form relative prime numbers. Consequently, of the 16 teeth of the crown wheel 37 only one tooth can enter each time entirely into an opposite tooth gap of the wheel 38, while the remaining teeth do not or only partially engage in the teeth gaps of the wheel 38. The number of the various reciprocal positions which the two wheels 37 and 38 can occupy relatively to one another, each of which is assured by the engagement of one movable tooth in a tooth gap of the opposite crown wheel, is equal to the product of the two numbers of teeth, thus in the case in question 840, so that the difference in the position of the paper carriage amounts to only 1/840th part of a revolution. The same fine adjustment is obtained in the case of the crown wheels 42 and 45, by means of which the stop 40 is adjusted. It is to be noted here that the position of the stop 40 must be assured in two directions, on the one hand against the action of the spring 43 tending to move the stop in the direction of the normal rotation of the wheel 14, and on the other hand against a rearward motion by the paper carriage, or by the stop 39, when the paper carriage is to be placed backward to this stop. Now the ratchet teeth of the wheels 42 and 40 are so arranged that the motion of the stop 40, which might be brought about by the rearwardly-moving paper carriage, must take place opposite to the direction of the ratchet teeth, so that a too great rearward movement is rendered impossible. The reverse motion, however, is not possible without disconnecting the clutch between the wheels 42 and 45, because in this event the spring 43 would have to move back a number of teeth of the wheel 45. This can be readily prevented by making the springs which keep these teeth in engagement with the wheel 42 sufficiently powerful to offer sufficient resistance to the action of the spring 43. The clutches formed by the crown wheels are disconnected in each case, as required, by means of the levers 34, 49 and 50. Lever 49, which coacts with the flange 47 is revolvable around the pivot 54 and carries at its end a roller 58 lying on the

cam 59. The pivot 57 is secured on a sliding carriage 61 which can move somewhat longitudinally. (Figs. 2 and 3.) A lever 62 revoluble around the pivot 63 is pivoted 5 to the slide 61. (Figs. 2 and 10). At the lower end of the same there engages a detent 64 which is generally pulled by a spring 65 in front of the lower end of the lever. The detent 64 is connected by a draw rod 66 10 with a lever 67. The latter is secured on a key-shaft 68 which carries at its end the key 68^a which is for eliminating an incorrect word, *i. e.* the word-canceling key. The cam 59 is secured on an axle 70 which carries in 15 addition the cam 71. Against the latter there rests the roller 72 provided at the end of one arm of the lever 34 which is revoluble around the fixed pivot 73. The shaft 70 is generally stationary and is only driven 20 when the paper carriage is to be moved backward, *i. e.* when the end-of-line key, the line-canceling key and the word-canceling key are struck. In this event the shaft 70 is coupled with the source of power operating the 25 perforating apparatus, whereupon it rotates once and then automatically stops. The coupling devices are not more particularly described because they may be made in any optional manner well-known in itself. 30 In the normal position of shaft 70 the rollers 58 and 72 are in recesses in the cams 59 and 71. If the shaft 70 is moved by striking the end-of-line key or the line-canceling key, the rollers 58 and 72 are forced out of the recesses in the cams 59 and 71 and cause the levers 34 and 49 to rock around their fulcrums 73 and 57, respectively. Lever 34 then draws the bushing 32 back, the ratchet teeth 44 of the crown wheel 42 being also 40 drawn back and withdrawn from the crown wheel 42 by means of the lever 49. This crown wheel 42 is driven, during the backward movement of the paper carriage and the wheels 11, 13 and 14, by the stops 39 and 45 40 and likewise arrives back into the position for the beginning of a line. If the word-canceling key is depressed, the action of the cam 59 is negated and the paper carriage runs only until the stop 39 abuts 50 against the stop 40.

The main shaft 78 and the auxiliary shaft 70 are driven by an optional source of power which first acts on a grooved pulley 145 mounted loosely on the main shaft 78. With 55 the grooved pulley 145 is connected a smaller grooved pulley 146 and from this a cord 147 leads to the grooved pulley 148 mounted loose on the auxiliary shaft 70. The three grooved pulleys are constantly under the action of the source of power and rotate continuously. Crown wheels 149 and 150 are respectively connected with the grooved pulleys 146 and 148 and participate in the continuous rotation of the pulleys. Opposite the crown wheel 150 is a pawl 151 which 60 is under the influence of a spring 152 and tends to enter between the teeth of the crown wheel 150. The pawl is secured revolubly by means of a pin 153 to a disk 154, and when the pawl 151 falls into a gap in the 70 crown wheel this disk is compelled to participate in the rotation of the wheel. With the disk 154 is firmly connected the auxiliary shaft 70, so that this also must participate in the rotation of the wheel. In its position of rest 75 the pawl is prevented by a lever 155 from being connected with the crown wheel, but when this lever is pulled away the pawl is connected with the crown wheel and the auxiliary shaft rotates with the grooved 80 pulley 148. But before one rotation is finished, the lever 155 returns into its normal position and a slanting face 156 on the lever receives the pawl 151 and lifts it out of the teeth of the crown wheel. The clutch which 85 temporarily connects the grooved pulleys 145, 146 with the main shaft 78 is arranged in exactly similar manner. Opposite the crown wheel 149 is the pawl 160 which is under the action of a spring 161 and tends 90 to engage in the teeth of the crown wheel (Fig. 3). The pawl is pivotally connected under the pin 162 to the disk 163 carrying the latter. In its normal position the lever 164 supports the extension of the pawl 160 95 and prevents it engaging in the teeth of the crown wheel. Now if any key is struck, any one of the plates 103 is displaced. Besides the projections 110, noses or lugs 165 are provided in addition on these plates. In 100 front of these noses or lugs is a cross-bar 166 which is likewise moved when a plate 103 is displaced. The bar 166 coacts with a lever 167 which is fulcrumed on the screw 168 and imparts its rotation caused by the cross-bar 105 by means of a link 169 to the lever 164. Consequently, a displacement of one of the plates 103 rotates the lever 164. This lever releases the pawl 160 so that it falls into the teeth of the crown wheel 149. Consequently, the disk 163 and the main shaft 78 rigidly connected therewith are temporarily 110 coupled with the continuously rotating grooved pulley 145. When the main shaft 78 and with it the disk 163 and the pawl 115 160 have rotated half a revolution the pawl 160 meets with a second arm 170 of the lever 164. The arm 170 possesses at its end a slanting face 171, on which the pawl runs when it is rotated further. It is thereby lifted out of the teeth of the crown wheel 149 and consequently becomes stationary. If the key which has been struck is now released, the plate 103, the bar 166 (the latter 120 under the action of the spring 172) the levers 167, 164 and 170 return into their normal positions. The lever 170 releases the pawl 160 which falls afresh into the teeth of the crown wheel 149 and rotates until it arrives on the slanting face 163 of the lever 130

164 and is raised again from the crown wheel at this place. The main shaft has now rotated one complete revolution and by means of the cam 121 has both pushed the punch through the paper and withdrawn it, and also has fed the ratchet wheels 16 to 19 one tooth by means of the pawl 139.

In order to bring the auxiliary shaft 70 into operation by means of the word-canceling key, I provide on the lengthened shaft 68 of the word-canceling key 68^a at the rear of the apparatus a small lever 175 which coacts by means of a pin 176 with the underside of one arm of an angle lever 177. The second arm of this angle lever is formed as a catch 178. This abuts against a lug 179 on the lever 180 which forms with the lever 155 an angle lever fulcrumed on the screw 181. At the free end of the lever 180 is a roller 182 and a leaf-spring 183 coacts with the underside of the lever. The roller 182 is opposite the cam disk 163 on the main shaft 78 and this disk has projection 184 and adjacent thereto a recess 185. When the word-canceling key is struck, the pin 176 lifts the lever arm 177 whereby the catch releases the lug 179. The roller 182 on lever 180 then lies, in consequence of the action of the spring 183, against the cam disk which at first prevents the lever 180 moving further. When the rotation of the main shaft 78 and the disk 163 is almost completed, the roller 182 falls into the recess 185. The lever arm 180 then moves and with it the lever arm 155 so far that the catch 151 slides from the end of the lever arm 155 and the auxiliary shaft 70 is thereby coupled with the continuously rotating grooved pulley 148. When the main shaft 78 rotates further the projection 184 of the disk 163, the levers 180 and 155 return into their normal positions in which they are held again by the catch 178. In this position the lever 155 again receives the catch 151 after the auxiliary shaft 70 has completed one revolution, and releases the connection between the grooved pulley 178 or the crown wheel 150 and the auxiliary shaft 70 so that the latter is again stationary. The catch 178 is influenced by the line-separating key and by other keys, which are for setting the auxiliary shaft 70 in operation, as well as by the word-canceling key. This is obtained in a simple manner by arranging on the catch 178, besides the lever arm 177, additional lever arms 186 which are under the influence of a lever 187 arranged on the shaft connected with the line-separating key. In addition to the two lever arms 187, 186 additional lever arms 60 may be arranged on the locking device so that these may be influenced by an optional number of keys.

By means of the word-canceling key the shaft 68 is rotated and the end of the lever 67 is moved downwardly; by means of the

draw rod 66 this lever pulls the catch 64 away from the end of the lever 62. Consequently the bottom end of the lever 62 can move outwardly unimpededly. If the cam 59 now acts on the roller 58 of the lever 49, the flange 47 and the bushing 46 are not, but the pivot 57 and its sliding carriage 61 against the action of the spring 60 are displaced. The latter is considerably weaker than the simultaneously-acting, fifteen springs of the ratchet teeth of the wheel 45. Consequently this wheel remains in engagement with the wheel 42 and the latter is prevented from moving backward, so that the paper carriage comes to rest as soon as the stop 39 has reached the stop 40. The cam 71, lever 34 and crown wheel 37 act in the case of this key exactly as in the case of the end-of-line key or in the case of the line-canceling key. After the word-canceling key has been depressed the paper carriage should occupy that position in which it was before beginning the canceled word. To this end, when finishing a word or when beginning a new word the stop 40 must pursue the stop 39 and be at once fixed again. Whenever the word separating key is struck, the connection of the crown wheels 45 and 42 is broken. For this reason the lever 50 is provided which coacts with the flange 48. This lever can rock around a pivot 75 and carries at one end a roller 76 lying against a cam 77. The roller 76 is on the main shaft 78 of the apparatus which is driven whenever a key is struck and stops after one revolution. The roller 76 is in a recess of the cam 77 and is influenced by the cam in like manner as the rollers 58 and 72 are influenced by the cams 59 and 71. The lever 50 operates, however, only when the word separating key is struck, because the pivot 75 is secured, like pivot 57, on a sliding carriage 79 movable longitudinally, to whose free end a lever 80 is pivoted. This lever can rock around the pivot 81 and is held at its lower end temporarily by a detent or catch 82. This catch forms the end of a lever 84 rocking around pivot 83 and attached at its other end to a driving rod 85 which is connected by the lever 85^a with the shaft 86 of the word-separating key. When any key other than the word-separating key is depressed, the shaft 78 is actuated without the lever 50 disengaging the crown wheel 43 from the crown wheel 42, namely the lever 50 rocks around its forked end, while the pivot 75 and the slide 79 reciprocate under the action of the spring 87. The lever 80 participates in this motion of the slide 79 and rocks around pivot 81. When the word separating key is struck, the shaft 86 rotates and drives the lever 84 by means of the rod 85, the catch 82 coming in front of the end of the lever 80. If the main shaft now operates, the rotation 130

of lever 80 and with it the motion of the slide 79 is prevented, so that the lever 50 must now rock around the pivot 75. Consequently the forked end of the lever presses 5 against the flange 48 and pulls the movable teeth 44 of the crown wheel 45 out of the crown wheel 42. Consequently the crown wheel 48 is no longer checked by the teeth 44 and rotates under the influence of the 10 spring 43 so that the stop 40 pursues the stop 39. After the complete revolution of the main shaft 78 the roller 76 falls again into the recess in the cam 77 and the teeth 44 again enter into the crown wheel 42, so that 15 this is again checked from moving further. If, when canceling a word, not only this but also the previous spacing element is to be canceled, the adjustment of the stop 40 must be completed before the paper carriage is 20 fed corresponding to the space. This can be brought about by suitably shaping the cam 77. For example, the recess in this cam may be made so large that during that part of the rotation of the main shaft 76 which 25 serves for actuating the wheels 16, 17, 18 and 19, the roller 76 lies in the recess of the cam 77 and exercises no action on the lever 50.

The operations when using the individual keys are as follows: In the case of the end-of-line key the auxiliary shaft 70 is coupled with the source of power, which operates the perforating apparatus, during one revolution of the auxiliary shaft and is automatically disconnected therefrom after the first 30 revolution. The two cams 59 and 71 withdraw the teeth of the crown wheels 37 and 45 from the crown wheels 38 and 42. In this manner both the wheel 14 and also the arm 41 become free, so that both move backward 35 under the influence of the spring at the paper carriage up to the beginning-of-line position. The spring on the paper carriage is not shown on the drawings; it may be arranged as well known from ordinary 40 type-writers but with the difference before mentioned, that it must move the carriage backwardly instead of forwardly. In addition, when the end-of-line key is struck an end-of-line symbol is perforated. The perforating devices for this may be of optional 45 kind and are therefore not herein-described. When the line-canceling key is struck the same action occurs, with regard to the backward movement of the paper carriage, as 50 when the end-of-line (canceling) key is depressed. The line-canceling symbol is simultaneously perforated in the band. When the word-canceling key is struck the auxiliary shaft 70 is likewise coupled with the 55 source of power, which drives the perforating apparatus, and is disconnected therefrom after one revolution. The catch 64, however, is simultaneously withdrawn from the end of lever 62 by the lever 67 of the 60 word-canceling key, and the cam 59 is there-

by made inoperative. Consequently, the wheel 14 with the paper carriage can only move backward, but not the stop 40 which is held by the teeth of the crown wheel 45. The paper carriage can now only run back 70 until the stop 39 abuts against the stop 40 whereby the further backward movement of the paper carriage is checked. As the stop 40, when setting a space, follows the stop 39 until it contacts with the same, the paper carriage is moved backward always the length of the last written word. When the space key is struck the stop 40 is readjusted by the cam on the main axle of the perforating device temporarily disconnecting the 80 crown wheel 45 from the crown wheel 42. In consequence of the action of the spiral spring provided between the wheels 42 and 14, the crown wheel 42 with the arm 41 and stop 40 follows the stop 39 until the stops 85 39 and 40 contact one another. The stop 40 is then held until the space key is struck again.

What I claim as my invention and desire to secure by Letters Patent is:

1. In apparatus for making perforated bands for automatically setting type, which bands when containing errors also contain representations of eliminating or canceling actions, the combination, with a type space indicator, of a member moved forward correspondingly by the same, a stop for coacting with, and preventing the backward movement of, said member, and means for setting said stop corresponding to the beginning of one or more groups of holes which are to be eliminated, whereby when the type space indicator moves backward, the same is stopped at a position corresponding to the first group of holes which are to be eliminated.

2. In apparatus for making perforated bands for automatically setting type, which bands when containing errors also contain representations of eliminating or canceling actions, the combination, with a type space indicator, of a member moved forward correspondingly by the same, a stop for coacting with, and preventing the backward movement of, said member, a spring acting on said stop and tending to cause the same to pursue the forwardly-moving member, and means for setting said stop corresponding to the beginning of one or more groups of holes which are to be eliminated, whereby when the type space indicator moves backward, the same is stopped at a position corresponding to the first group of holes which are to be eliminated.

3. In apparatus for making perforated bands for automatically setting type, which bands when containing errors also contain representations of eliminating or canceling actions, the combination, with a type space indicator, of a member moved forward cor-

respondingly by the same, a stop for coacting with, and preventing the backward movement of, said member, a spring acting on said stop and tending to cause the same to pursue the forwardly-moving member, and means comprising a clutch holding said stop against the action of said spring for setting said stop corresponding to the beginning of one or more groups of holes which are to be eliminated, whereby when the type space indicator moves backward, the same is stopped at a position corresponding to the first group of holes which are to be eliminated.

15 4. In apparatus for making perforated bands for automatically setting type, which bands when containing errors also contain representations of eliminating or canceling actions, the combination, with a paper carriage, revolute member (14, 38), having an abutment (39), operatively connected therewith, a clutch member (37) normally engaging said revolute member and forming therewith a clutch, a spring-pulled clutch member (42) having a stop (40) for coacting with said abutment, a third clutch member (45) normally engaging the latter clutch member (42) and forming a second clutch, a shaft (70) carrying two cams (59, 71), and means operatively connecting said cams with said clutches and arranged to disconnect the same when said shaft is rotated.

5. In apparatus for making perforated bands for automatically setting type, which bands when containing errors also contain representations of eliminating or canceling actions, the combination, with a paper carriage, of a revolute member (14, 38), having an abutment (39), operatively connected therewith, a clutch member (37) normally engaging said revolute member and forming therewith a clutch, a spring-pulled clutch member (42) having a stop (40) for coacting with said abutment, a third clutch member (45) normally engaging the latter clutch member (42) and forming a second clutch, a shaft (70) carrying two cams (59, 71), a lever (34) engaging the former clutch member and actuated by one of said cams to disengage the former clutch, a second lever (49) engaging the third clutch member and normally actuated by the other of said cams to disengage the second clutch, the latter lever being fulcrumed on a slide (61), and detachable locking means securing said slide in its normal position whereby when said shaft is rotated, said clutches are disengaged.

6. In apparatus for making perforated bands for automatically setting type, which bands when containing errors also contain representations of eliminating or canceling

actions, the combination, with a paper carriage, of a revolute member (14, 38), having an abutment (39), operatively connected therewith, a clutch member (37) normally engaging said revolute member and forming therewith a clutch, a spring-pulled clutch member (42) having a stop (40) for coacting with said abutment, a third clutch member (45) normally engaging the latter clutch member (42) and forming a second clutch, an auxiliary shaft (70) carrying two cams (59, 71), a lever (34) engaging the former clutch member and actuated by one of said cams to disengage the former clutch, a second lever (49) engaging the third clutch member and normally actuated by the other of said cams to disengage the second clutch, the latter lever being fulcrumed on a slide (61), and detachable locking means securing said slide in its normal position whereby when said shaft is rotated, said clutches are disengaged, an intermittently rotating main shaft, carrying a cam (77) a slide (79), a lever fulcrumed on the latter, engaging the third clutch member, and carrying a roller coacting with said cam (77) on said main shaft, and detachable locking means for securing the latter slide (79) in position.

7. In apparatus for making perforated bands for automatically setting type, which bands when containing errors also contain representations of eliminating or canceling actions, the combination, with a paper carriage having a rack, of an axle (15) a crown wheel (38) having an abutment (39) loose on said axle and geared with said rack, a second crown wheel (37) comprising spring-pressed, axially-movable teeth movable axially on and rotatable with said axle and forming with the former crown wheel a clutch, a third, spring-controlled crown wheel (42) loose on said axle, the latter crown wheel having a stop for coacting with said abutment, a fourth crown wheel comprising axially-movable, spring-pressed teeth rotatable and axially-movable on said axle and forming with the third crown wheel a second clutch, a main shaft, a lever engaging said fourth crown wheel and actuated by said shaft, an auxiliary shaft carrying two cams, and levers operatively connecting the latter cams with said clutches for disconnecting the same.

In testimony whereof I have signed my name to this specification in the presence of two subscribing witnesses.

HEINRICH DREWELL.
